ROAD ROLLER

Bryant Essick, Los Angeles, Calif., assignor to
 Essick Manufacturing Company, Los Angeles,
 Calif., a corporation of California

Application March 30, 1946, Serial No. 658,507

3 Claims. (Cl. 180—20)

1

This invention has to do with a road roller and it is a general object of the present invention to provide a road roller of simplified improved economical construction and which is improved in operation.

Rollers commonly referred to as road rollers are used extensively for various purposes but generally for rolling earth or for rolling materials employed in the construction of roads or the like. It frequently occurs in the use of a road roller that it is employed on a surface that is hard enough or firm enough to support the roller if it is in motion, but which allows the roller to sink into it if the roller is allowed to stand even momentarily. With the ordinary construction employed in road rollers the direction of movement of the roller or vehicle is controlled through a suitable clutch or gear mechanism usually through a combined clutch and gear, much the same as is found on a motor vehicle, making it necessary in reversing the roller to first bring the roller to a stop, then disengage the clutch, then change the gears throwing them into reverse, and then re-engage the clutch. During the interval that the clutch is disengaged and the gears are being reversed the roller is standing still or practically still in one spot and it is this standing of the roller or this dwell that will cause the roller in many cases to settle into the surface being rolled, causing an undesirable indentation.

It is a general object of my present invention to provide a road roller involving a drive that is reversible making it possible to drive the roller in either direction which drive is such that the motion or movement of the roller can be reversed very rapidly or, in effect, instantaneously, so that there is no period of rest or dwell allowing the roller to sink into the surface on which it stands.

It is a further object of my present invention to provide a road roller of improved construction wherein the forward portion of the frame is in the nature of a head which not only effectively supports the yoke of the steering roller but also carries the mechanism of the steering gear and forms a convenient advantageously located seat on which the operator can ride. With the arrangement that I have provided the seat formed by the head of the frame is located in a most convenient and advantageous manner relative to the steering wheel and relative to the controls so that the machine as a whole is compact and convenient to manipulate.

The various objects and features of my invention will be fully understood from the fol-

2

lowing detailed description of a typical preferred form and application of the invention, throughout which description reference is made to the accompanying drawings, in which:

Fig. 1 is a side elevation of the road roller embodying my present invention. Fig. 2 is a longitudinal detailed sectional view taken through the clutch unit and transmission showing the general arrangement and relationship of parts incorporated in these units of the machine, being a view taken substantially as indicated by line 2—2 on Fig. 1. Fig. 3 is a sectional view of the mechanism taken substantially as indicated by line 3—3 on Fig. 2 and Fig. 4 is a reduced sectional view taken as indicated by line 4—4 on Fig. 1.

The road roller or vehicle that I have provided involves, generally, a frame A, two rollers that support the frame, one a main drive roller 20 B and the other a steering roller C, a steering gear D for the steering roller C, a storage tank E preferably located in the region of the drive roller B, a prime mover F, a clutch unit G, a transmission or speed change mechanism H, and 25 a direct drive means J from the transmission H to the drive roller B.

The frame A that I have provided is of simple, inexpensive yet effective construction. It involves, generally, two spaced parallel side rails 30 10, a platform 11 carried between the side rails at the forward end portion thereof, and a head 12 carried by the forward ends of the side rails. The rails 10 may be simple, straight, horizontally disposed beams and the platform 11 may be a simple, flat plate extending between and anchored to the beams.

The head 12 of the frame forms a mounting for the steering roller C, or at least forms a part of the frame to which the steering roller is attached, and in accordance with my construction it involves, essentially, two spaced side plates 40 13, one carried by each of the beams 10, which plates extend up and forward from the beams in the manner clearly shown in Fig. 1. The head 45 further includes a plate that extends between the side plates 13 and has a vertical section 14 extending upwardly from the forward end of the platform 11 to a point a substantial distance above the platform and a horizontal section 15 50 which extends forward from the upper end of the section 14 between the plates 13 to a point where it joins a transverse head beam 16. The section 14 may be located somewhat forward of the vertical edges 17 of sides 13 and the section 55 15 may be located somewhat below the top edges

18 of the sides 13. The sections 14 and 15 are preferably secured, for instance, welded, to the sides 13 where they adjoin them and these parts thus form a rigid durable frame construction. The head beam 16 is preferably a tubular part extending between the forward end portions of the side plates 13 and has its ends joined thereto while the forward edge of the plate section 15 is preferably joined or welded to the beam 16. It is to be observed that the horizontal section 15 of the head construction just described forms a conveniently located and arranged support for a seat on which an operator can sit while his feet are on the platform 11.

The main or drive roller B is preferably a large roller and is preferably designed so that it can be weighted with water or the like. In the construction illustrated the roller includes a cylindrical rim 20 with end plates 21 closing it at the ends so that it is in the form of a large drum. A suitable access opening is provided and is normally closed by a removable plug 22 so that a suitable quantity of water or other heavy material can be arranged in the roller, if desired. The roller B is carried on an axle 23 supported by bearings 24 attached to the beams 10 and the parts are preferably proportioned so that the roller B operates between the beams 10.

The steering roller C may be a simple drum-like structure involving a rim 25 and end plates 26 closing the ends of the cylindrical rim. The roller C is carried by a yoke 27 which is provided with a king or pivot pin 29 that is pivotally connected to the head beam 16 of the frame. The head beam 16 is preferably provided with a downwardly facing boss 30 against which the yoke seats. The arms of the yoke that carry the roller C depend down at either end of the roller and they may carry a frame 31 supporting scrapers 32 as shown in Fig. 1 of the drawings. The steering gear D is provided for steering or turning the roller C about the pivot pin 29 and it is preferably carried by the horizontal section 15 of the frame head and somewhat to the center of the vehicle so that it does not obstruct the seating area provided by the section 15. The steering gear that I have shown involves, generally, a hand wheel 33 on the forward end of a horizontally disposed drive shaft 34 which drives a vertical shaft 35 through a suitable gear drive 36. The shaft 34 is located above the plate section 15 and projects somewhat forward thereof so that the wheel 33 is supported a short distance forward of the plate section 14, while the shaft 35 extends down through the plate section 15 and is operatively connected with the yoke 27 through a suitable link mechanism 38 so that when the shaft 35 is rotated the yoke 27 is turned on the pivot pin 29.

The storage tank E is preferably located over the drive roller B, and is preferably shaped to nest over the drive roller B. In the case illustrated the tank E involves flat ends 40, vertical flat sides 41 a flat top 42 and a concave bottom 43 which conforms to the curvature of the rim 20 of the roller B. A filling opening is provided in the top of the tank and is normally closed by a plug 44 and a suitable drain opening is provided in the lower part of the tank and is normally closed by a plug 45. The tank just described is supported on the beams 10 so that the load or weight thereof is communicated through the beams to the roller B. Suitable hoses or pipe lines 46 lead from the tank to the roller B and

C so water can be supplied to the rollers as the machine operates.

The prime mover F that I have provided is preferably an engine such as an internal combustion engine and it, together with the clutch means and transmission, forms a unit that is disposed transversely of the vehicle in the space that occurs between the tank of means E and the section 14 of the head of the frame, it being preferred to locate this unit immediately adjacent the tank so that there is space between the unit and the head of the frame where the operator can conveniently stand, which space is convenient to the steering wheel 33. The unit formed of the parts just described is preferably carried by a pair of supports 50 that extend transversely between the beams 10 to the desired point so that they effectively carry the unit.

The clutch means G that I have provided is a friction clutch means and involves two drive pinions 51 and 52 which are normally rotated in opposite directions. The pinion 51 may be directly mounted on and driven by the engine shaft 53 which projects into the housing 54 of the clutch mechanism, and which may be secured directly to the rear end of the engine housing 55. The pinion 52 is mounted on and driven by a countershaft 56 driven from the engine shaft through a gear 57 which preferably meshes with the pinion 51. It is to be observed that the shaft 56 is parallel to and offset from the engine shaft 53 and that the pinions 51 and 52 are spaced apart a substantial distance longitudinally of the clutch mechanism.

The clutch mechanism further includes two ring gears 58 and 58' which are rotatably supported on a shaft 59 rotated parallel to and a substantial distance below the engine shaft 53 and the countershaft 56. The ring gear 58 meshes with and is driven by the pinion 51 while the ring gear 58' meshes with and is driven by the pinion 52. The ring gears 58 and 58' carry clutch drums 60 which extend inwardly or oppose each other and have friction clutch units 61. The clutch units 61 are preferably of the multiple disc type under control of a single shiftable member 62 slidably splined on the shaft 59 between the ring gears. When the member 62 is shifted to the left in Fig. 2 the clutch unit 61 connected with ring gear 58 is engaged whereas when it is shifted to the right the clutch unit in connection with ring gear 58' is engaged. The parts are related so that the member 62 has a neutral position through which it moves so that both clutch units are not engaged simultaneously. When either one of the clutch units is engaged the shaft 59 is driven, and through the gearing that I have described and which is shown in Fig. 2 it will be apparent that a substantial speed reduction is effected between the engine shaft 53 and the shaft 59.

The shiftable member 62 which controls the clutch units 61 can be shifted in any desired manner, for instance by means of a conventional shift lever 63 mounted on the exterior of the housing 54 which lever operates a suitable yoke or shifting device 64 located within the housing 54 and which serves to move the member 62 in the desired manner.

The transmission H is a change speed mechanism and may, in practice, involve gears through which any desired number of speed ratios can be obtained. In the particular case illustrated the mechanism is such as to gain two different speeds or drives.

The transmission as shown in the drawings includes, generally, a housing 70 and drive pinions 71 and 72 located in the housing 70 on an extension 73 of shaft 59. The pinions 71 and 72 are of different sizes, the pinion 72 being considerably larger than pinion 71, and are spaced a substantial distance apart on the shaft extension 73.

The transmission involves a countershaft 74 located parallel to and offset from the shaft extension 73 and a gear unit 75 is slidably mounted on or splined to the countershaft. The gear unit 75 involves gears 76 and 77 which mesh with the pinions 71 and 72, respectively. When the gear member 75 is shifted to the left gear 76 meshes with and is driven by pinion 71 and the relative speed between shaft extension 73 and shaft 74 is determined by the relationship of the pinion 71 and gear 76, whereas when the gear member 75 is shifted to the right the gear 77 meshes with and is driven by pinion 72 and the relative speed between shafts 73 and 74 is determined by the relationship between the pinion 72 and the gear 77. The housing 70 of the transmission is preferably rigid with, in fact, it may be an integral continuation of the housing 54, as shown in the drawings, and a suitable means may be provided for shifting the gear member 75 between the two positions above described. In the drawings I have shown a conventional shift lever 80 projecting from the exterior of the housing 70 and a yoke device 80^a is operated by the lever 80 within the housing to engage and shift the gear member 75 as desired.

The drive means J that I have provided between the unit just described and the roller B is preferably a simple direct drive which effects a substantial speed reduction between the shaft 74 and the roller. The shaft 74 has an extension at the exterior of the housing 70 which extension carries a drive sprocket 81. A driven sprocket 82 is carried by the roller B and a chain 83 connects the sprockets 81 and 82. It will be observed from the drawings that the sprocket 82 is very much larger than the sprocket 81 with the result that a substantial speed reduction is effected in the course of the drive from the transmission to the roller.

From the foregoing description it will be apparent that I have provided a vehicle or roller that can be varied in action by varying the material carried within the roller B and further it will be observed that the principal working parts are confined to the unit formed by the engine, clutch means and transmission, and that this unit is arranged convenient to the operator and transverse of the vehicle. The only exposed drive parts are the chain and sprockets and, in practice, these may be housed by suitable guards 90 and 91, if desired. The shift levers 63 and 80 are convenient to the operator and the hand wheel 33 by which the vehicle is steered is located in a most convenient location so that the operator can either sit on the horizontal section 15 of the frame as the vehicle is being operated, or he can stand on the platform 11 as he desires. When the operator is seated on section 15 beside the steering gear or beside the hand wheel 33 the hand wheel is adjacent him and his feet may rest on the platform 11. To work the clutch or transmission controls the operator needs only to lean over or forward and to reach out to the controls. If the operator stands on the platform he is in easy reach of the controls and also the wheel. In manipulating the vehicle the transmission is

normally set at either one speed or the other by shifting the member 15 to one side or the other. With the transmission thus set it can be left alone and it will determine the general speed of the roller except of course for control gained through the speed at which the engine is operated. To disengage the drive so that the vehicle is not driven by the engine the member 62 is positioned in a central or neutral position. To drive the roller in one direction or the other the lever 63 is manipulated engaging the desired clutch unit 61. The shift between one clutch unit 61 and the other can be made very rapidly, this is, by merely swinging the lever 63 from one extreme position to the other, with the result that the roller will change direction without a hesitation or dwell such as is undesirable as above described.

The particular frame construction for road rollers hereinabove described is the subject of my copending application Serial No. 756,499, filed June 23, 1947, entitled "Road Roller Construction," which application was filed as a division of this application.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A road rolling vehicle including, an elongate rigid frame having spaced side beams and an upwardly and forwardly projecting head rigid with and projecting from the beams at one end of the frame, a drive roller, mounting means rotatably supporting the roller and carried by and between the beams, a steering roller carried by the head of the frame, and means carried by the frame for operating the drive roller including a power unit carried by the frame and a drive from the power unit to the drive roller, the unit including an engine, and a reversible friction clutch for reversing the direction of movement of the vehicle.

2. A road rolling vehicle including, an elongate rigid frame having spaced side beams and an upwardly and forwardly projecting head rigid with and projecting from the beams at one end of the frame, a drive roller, mounting means rotatably supporting the roller and carried by and between the beams, a steering roller carried by the head of the frame, and means carried by the frame for operating the drive roller in either direction including, an engine operating in one direction, a power transmitting means engaged with the drive roller, two drive mechanisms each normally driven by the engine, one of said mechanisms having a driver operating in one direction and the other of said mechanisms having a driver operating in the opposite direction, and friction clutch means in driving engagement with the power transmitting means and selectively engageable with said drivers.

3. A road rolling vehicle including, an elongate rigid frame having spaced side beams and an upwardly and forwardly projecting head rigid with and projecting from the beams at one end of the frame, a drive roller, mounting means rotatably supporting the roller and carried by and between the beams, a steering roller carried by the head of the frame, and means carried by the frame for

operating the drive roller in either direction including, an engine operating in one direction, a power transmitting means engaged with the drive roller and including a speed change mechanism normally engaged for operation at a selected speed, two drive mechanisms each normally driven by the engine and having drivers operating in opposite directions and friction clutch means in driving engagement with the speed change mechanism and selectively engageable with said drivers to operate the power transmitting means in one direction or the other.

BRYANT ESSICK.
